UNITED STATES PATENT OFFICE.

LEAMAN A. MAIDEN, OF NEWBERRY, FLORIDA.

BOTTLE.

1,240,072.

Specification of Letters Patent. Patented Sept. 11, 1917.

Application filed July 19, 1916. Serial No. 110,132.

To all whom it may concern:

Be it known that I, LEAMAN A. MAIDEN, a citizen of the United States, residing at Newberry, in the county of Alachua and State of Florida, have invented certain new and useful Improvements in Bottles, of which the following is a specification.

This invention relates to bottles and like liquid containers and has as one of its objects to provide a container of this general type embodying means for housing one or more drinking cups in such manner as to maintain the cups in sanitary condition, although the container itself may be packed with other articles.

The invention also aims to provide a container with means whereby a spoon or similar article may be held assembled or packed therewith and in a manner to be protected.

20 In the accompanying drawings:

Figure 1 is a side elevation of the bottle embodying the present invention.

Fig. 2 is a similar view, the protective housing shell for the sanitary cups being 25 shown in vertical section.

Fig. 3 is a perspective view of the lower portion of the bottle and one of the said cups.

Fig. 4 is a horizontal sectional view taken 30 substantially on the line 4—4 of Fig. 2.

Fig. 5 is a detail horizontal sectional view taken substantially on the line 5—5 of Fig. 1.

In the drawings the numeral 1 indicates in general the body of the bottle or other 35 container and 2 the bottom thereof, the bottom being preferably flat, as shown in Fig. 2 of the drawings. The bottle is provided below its bottom with a base which is indicated by the numeral 3 and which is preferably flat and circular in outline, the edge or periphery of the base being rounded as indicated by the numeral 4 and as clearly shown in Figs. 1 and 2 of the drawings. The base is integrally connected with the 40 bottom 2 by means of web portions 5 which are cast with the bottle and base and are consequently of the same material as the said bottle. The webs 5 are here shown as four in number and as extending radially 45 with relation to the vertical axis of the bottle as a whole and these webs at their outer edges terminate flush with the exterior surface of the body of the bottle, and the base 4 is preferably of substantially the same 50 diameter as the bottom 2 of the bottle. The

webs 5 afford between them and the bottom 2 and base 4, pockets or compartments which are indicated by the numeral 6 and which receive sanitary drinking cups which are of segmental form as clearly shown in Fig. 60 3. Each of the cups includes two plane side walls 7 and an arcuate wall 8 and the cups are assembled with the bottle by disposing them within the compartments 6 in the manner shown in Figs. 2 and 4 of the drawings, 65 the angular sides of the cups fitting within the angle between the adjacent sides of the webs 5 and the outer surfaces of the walls 8 of the cups being flush with the outer surface of the body of the bottle. 70

In order to retain the drinking cups within their respective compartments and to reinforce and prevent fracture of the lower portion of the bottle when the same is packed with other articles, and further, in order to 75 exclude dust and dirt from the said cups and thereby maintain the same in sanitary condition, a protective housing shell 9 preferably of metal, is slidably fitted upon the body of the bottle and this shell, as will be 80 observed by reference to the drawings, is cylindrical and interiorly of a diameter to snugly fit the outer surface of the said body of the bottle. The shell is of a height somewhat greater than the height of the compartments 6 and, therefore, when the shell is 85 so applied to the bottle as to close the said compartments and protect the cups the upper portion of the shell will extend above the plane of the true bottom of the bottle and 90 the connection of the shell with the bottle will be rendered more rigid than would be the case if the upper end of the shell terminated at or close to the upper sides of the compartments. Furthermore, in this manner 95 fracture of the webs 5 is effectually prevented. The shell may be bodily removed from the body and thoroughly cleaned whenever desired and in order that the shell when fitted to the bottle may be held firmly in 100 place and against accidental upward slipping upon the body of the bottle, the said shell is provided at its lower end with a number of resilient fingers 10 which are designed to grip the convex or rounded edge 4 105 of the base 3 in the manner clearly shown in Fig. 2 of the drawings and for the purpose stated. In order that the fingers may grip the edge of the said base in the manner stated and yet in order to provide for re- 110

moval of the shell from the bottle without likelihood of the fingers catching against the bottom of the bottle, the said base is slightly larger in diameter than is the body of the 5 bottle exteriorly and the fingers will, therefore, clear the outer surface of the bottle as the shell is slid upwardly thereon.

In order that a spoon may be held assembled with the bottle and, therefore, be convenient for use, the bottle is provided in its 10 side with a recess 11 which is of a width, depth and length to receive and properly house one or more spoons indicated by the numeral 12. The recess 11 extends nearly to 15 the bottom 2 of the bottle and consequently the lower portion of the recess is designed to be closed by the upper portion of the shell 9. In this manner the handle of the spoon will be so confined as to insure of the spoon 20 being properly supported within the recess and yet the spoon may be conveniently removed when it is desired to use the same.

It will be understood, of course, that more than one of the recesses 11 may be provided 25 in the body of the bottle and that the number of compartments 6 may be varied as desired, as also the contour of the said compartments.

Having thus described the invention, what 30 is claimed as new is:

1. A container provided with a base spaced from its bottom, webs connecting the base and bottom and dividing the space between the said base and bottom into compartments, 35 receptacles disposed within the compartments, and a shell fitted upon the container

and movable to close the said compartments and retain the receptacles therein.

2. A container provided with a base spaced from its bottom, webs connecting the base 40 and bottom and dividing the space between the said base and bottom into compartments, receptacles disposed within the compartments, and a shell slideable upon the body of the container and arranged when in lowered 45 position to close the said compartments and retain the receptacles therein.

3. A container provided with a base spaced from its bottom, webs connecting the base and bottom and dividing the space between 50 the said base and bottom into compartments, receptacles disposed within the compartments, a shell slideable upon the body of the container and arranged when in lowered position to close the said compartments, and 55 retain the receptacle therein, and means for holding the shell against upward displacement.

4. A container provided with a base spaced from its bottom, webs connecting the base 60 and bottom and dividing the space between the said base and bottom into compartments, receptacles disposed within the compartments, a shell slideable upon the body of the container and arranged when in lowered 65 position to close the said compartments and retain the receptacles therein, and latch fingers carried by the shell and constructed to engage the edge of the said base whereby to hold the shell against upward displacement. 70

In testimony whereof I affix my signature.
LEAMAN A. MAIDEN. [L. S.]
